UNITED STATES PATENT OFFICE

100,542

DESIGN FOR AN ELECTRIC IRON

Fredrick David Chapman, Evanston, Ill., assignor
to Montgomery Ward & Co., Incorporated,
Chicago, Ill., a corporation of Illinois

Application May 27, 1935, Serial No. 57,044

Term of patent 3½ years

To all whom it may concern:

Be it known that I, Fredrick David Chapman, a citizen of the United States, residing at Evanston, in the county of Cook and State of Illinois, have invented a new, original, and ornamental Design for an Electric Iron, of which the following is a specification; reference being had to the accompanying drawing, forming a part thereof.

In the drawing,

Fig. 1 is a perspective view of an electric iron showing my new design;

Fig. 2 is a side elevation thereof; and

Fig. 3 is a top plan view of the iron.

I claim:

The ornamental design for an electric iron, as shown.

FREDRICK DAVID CHAPMAN.
